UNITED STATES PATENT OFFICE.

VINCENT LOMBARDI, OF BROOKLYN, NEW YORK.

KNITTING MACHINE.

Application filed September 17, 1925. Serial No. 56,895.

This invention relates to knitting machines and methods and more particularly it relates to machines and methods for knitting fabrics of a plurality of independent 5 yarns, for example, multicolor fabrics.

An object of the invention is to provide a fabric comprising a plurality of yarns so combined as to produce a strong and durable structure presenting any of a wide variety of 10 pleasing effects and designs.

Another object is directed to the provision of a knitting machine which is simple in construction, economical of manufacture and assembly, readily adjustable, 15 capable of a wide variety of uses and adapted for ready and efficient operation.

Another object is to provide means for producing a predetermined variation in the rise and fall of the needles of a knitting 20 machine to cause desired variations in the fabric.

Another object is to provide means for securing the individual control of the knitting operations of a plurality of needles, 25 particularly advantageous when the needles are all similar as to shape and size.

Another object is to provide means for securing automatically the individual control of all the needles of a machine to cause 30 the production of a fabric from a plurality of independent yarns in which a yarn not appearing in the front of the fabric at any particular point is interlocked behind and between the loops of the yarn which does 35 form loops in the front of the fabric at that point.

Another object is to provide special cam means to insure that the interlocked fabric is firmly knitted particularly that the interlocked yarns in the back of the fabric are 40 tightly drawn to prevent any looseness or dangling yarns.

Other objects of the invention will in part be obvious and will in part appear herein- 45 after.

The invention accordingly comprises the several steps and the relation and order of one or more of such steps with respect to each of the others, the apparatus embodying 50 the features of construction, combination of elements and arrangements of parts adapted to effect such steps, all of which will be exemplified in the following detailed disclosure and the scope of the application of 55 which will be indicated in the appended claims.

For a fuller understanding of the nature and objects of the invention reference should be had to the following detailed description taken in connection with the accompanying drawings in which Fig. 1 represents a general plan view of the machine of 60 this invention; Fig. 2 is a sectional view of the machine illustrating the automatic control of the knitting operations of a representative needle; Fig. 3 is a sectional view of the certain cams attached to a rotating cylinder; Fig. 4 illustrates the pattern drum mechanism for the machine; Fig. 5 is an end view in section of one of the pattern 65 drums; Fig. 6 is a somewhat diagrammatic showing of the cylinder needles in their various operating positions with their associated control apparatus arranged to produce a certain type of fabric; Fig. 7 is a fragmentary view in a plurality of sections in 70 different horizontal planes to illustrate the construction of the machine; Fig. 8 illustrates the position of the control apparatus 75 of a needle when the needle is prevented from knitting; Fig. 9 illustrates the needle control apparatus when the needle is in its full knitting position.

Referring more particularly to Fig. 1, the knitting machine disclosed is of the circular type employing cylinder needles and in the specific type taken for illustration two yarn carriers 1 and 2 are provided. It will be assumed for convenience that the yarn from carrier 1 is blue and the yarn from carrier 2 is white so as to give a two color fabric the design of which may be varied. The cylinder needles are controlled automatically in the knitting by paper patterns located on four rotatable drums 3, 4, 5 and 6, each 80 drum being adapted by mechanism herein- 85 after described to control the cylinder needles in the adjacent quadrant of the machine, so that the four drums provide for the automatic control of all of the cylinder 90 needles in the entire circumference of the machine.

Power for driving the machine may be obtained from a motor 7 which drives a shaft 8. Shaft 8 by suitable gears is coupled 105 to shafts 9 and 10 so that these latter shafts are driven in a clockwise direction. Shaft 10 is geared at its end to rotate a shaft 12 which as will be described later controls the pattern drum 3. Similarly, shaft 9 is geared 110 to a shaft which drives pattern drum 5. Attached to the end of the main shaft 8 is

a gear which meshes with a toothed ring 13 to which are fastened the various parts of the machine which are to be rotated. On the opposite side of the machine from shaft 8 is a shaft 14 driven by gear means from the toothed ring 13. Shaft 14 in turn drives two shafts 15 and 16 which in turn drive controlling shafts for the pattern drums 4 and 6, respectively.

10 The ring 13 is attached at the points 17 and 18 with the cam ring 19, which supports the cams for raising and lowering the needles, as hereinafter described. The cam ring 20 for moving the customary 15 sinkers in and out is connected by members 22 and 23 to the cylinder cam ring 19. The other parts of the machine appearing in Fig. 1 will be explained in detail in connection with Fig. 2 which gives a vertical sectional 20 view taken at the point indicated in Fig. 1.

The slotted cylinder 24 for holding the cylinder needles is shown at the extreme left of Fig. 2. One of the latched cylinder needles 25 is shown in a vertical slot in cylinder 24, the cylinder needles being held in their respective slots by wires 26, 27. Above the needle cylinder 24 lie the usual sinkers 28 and the rotating sinker cam 20. The yarn carrier 1 is supported from the sinker cam 25 30 in the usual manner. The rotating sinker cam 20 slides in a groove in the stationary member 30 which is suitably mounted on a stationary cylinder 32, which in turn, rests on the base plate 33. The toothed or ring gear 13 rotates in a groove in plate 33 while the needle cam cylinder 19 also rotates in a groove in the same plate. The gear ring 13 and the needle cam cylinder are connected by member 17, as shown also in Fig. 1. A post 35 40 rising from the rotatable cylinder 19 serves to support the member 22 which is fastened to the sinker cam 29. Arising from and integral with the annular plate 35 which connects the needle cylinder 24 with the base 45 plate 33 is an upright piece 36 which in addition to having a groove in the top thereof of running around the machine also has a deep radial slot 38 opposite each cylinder needle. Lying in the circumferential groove 50 37 is a wire 39 and lying on top of wire 39 in each radial slot is a needle lever 40. Each lever 40 is pivoted on the wire 39 due to a deep groove 42 on its underside into which the wire fits snugly. The radial slot 55 in member 36 into which the lever 40 fits should be designed to prevent an appreciable side play of lever 40 while still permitting the lever to rotate on its pivot. One end of lever 40 ends in 60 two jaws which fit around the needle butt so that the movement of lever 40 will cause a rise or fall in its associated needle. In the other direction lever 40 ends between two jaws of an upright operating member 43 for 65 the lever. The upper end of member 43 fits into a slot 44 in the stationary member 30, while the lower end of member 43 fits into a slot 45 in the base plate 33. Slot 44 allows an upward and downward movement of member 43 but permits no side play in either transverse direction. Slot 45, however, allows considerable lateral movement of the lower end of member 43 in a direction parallel to the plane of the drawing but permits no lateral movement in a direction at right angles to the plane of the drawing. Slot 45 also permits an upward and downward movement of member 43. It should also be noted that the stationary cylinder 32 is slotted to receive the end of lever 40.

In Fig. 2 the lever operating member 43 is in its uppermost position to which it has been raised by the passage of a cam 46 (see Fig. 8) which contacted with the lower side of projection 48 to fully raise member 43 to the position shown in Fig. 2. Projection 48 is of such a size that cam 46 will in each passage contact with the lower side thereof to raise member 43 to its uppermost position provided the lower end of member 43 has been moved to its extreme right position. Referring again to Fig. 8 it will be seen that if member 43 is moved only partially to the right another cam 41 will contact with the lower side of projection 48 and since cam 41 is smaller than cam 46, this will produce only a partial raising of the lever operating member 43.

Near the lower end of cylinder 19 are mounted two additional cams 49 and 50. These additional cams are such that depending on the lateral position of member 43, the member 43 will at times be lowered by cam 49 and at other times will be lowered by the passage of cam 50 due to contacting with the upper side of projection 48; and at still other times will not be lowered by the passage of either cam 49 or 50. Due to their relative sizes cam 50 will lower member 43 only a small distance and cam 49 will lower it a greater distance for reasons which will appear hereinafter. The relations of cams 41, 46, 49 and 50 are such that any needles raised by cam 49 will be lowered by cam 46 and any needles raised by cam 50 will be lowered by cam 41.

Slot 45 which passes entirely through the base plate 33 also holds a horizontally operating member 52 which is U-shaped in one portion 53 thereof to form a pocket for the lower end of member 43 so as to be a guide therefor whenever member 52 is moved horizontally. One end of member 52 is fitted to receive the end of a spring 54 which at its other end fits into a groove in the side of base plate 33. The action of spring 54 is such as to tend to pull member 52 in the direction of the center of the machine. The other end of member 52 is fastened to the end of a flexible wire 55 which is used to control

the position of member 52 determined by pattern mechanism hereinafter described. Wire 55 throughout the greater portion of its length is surrounded by a rigid tubing 56 which may be of metal if desired. Tubing 56 prevents any side play or lost motion in wire 55 while still permitting wire 55 to move longitudinally thereof. Tubing 56 is embedded in some suitable compound 10 57 for maintaining tube 56 in its desired position.

The arrangement by means of which wire 55 is controlled by a paper pattern will now be described. Fig. 2 at the right shows an 15 end view of the pattern drum 3. Pivoted about a shaft 58 is an angle member having two arms 59 and 60. Pivoted also about shaft 58 is an arm 62 to the lower end of which is attached the end of wire 55. Arm 20 60 is normally held away from arm 62 a desired distance by means of an adjustable screw 63. The free end of arm 59 is provided with a threaded plunger 64 the lower end of which continues as a pin 65 of much 25 smaller diameter than the main body thereof. The plunger 64 is normally held in contact with the pattern paper on drum 3 due to the pull of spring 54 through wire 55. If there happens to be a small hole in the paper underneath plunger 64 the pin 65 will enter the hole until the main body of the plunger rests on the paper. If there is a large hole in the paper the main body of the plunger 64 will project therethrough a much greater 35 distance.

Referring to both Figs. 1 and 2, it will be seen that with reference to drum 3 there are also pivoted about shaft 58 two spaced cams 68 joined by a rod 69. Each of these cams 40 68 contains a slot 70 which surrounds the rotating shaft 12. Mounted on the rotatable shaft 12 and located within the slot 70 is an eccentric 72 which by the rotation of shaft 12 gives an oscillating movement to cam 68 about shaft 58. In Fig. 2 the cam 68 is shown in its maximum counter-clockwise position and in this position cam 68 by means of rod 69 moving against arms 60 causes all the plungers 64 to be raised away from the 45 paper pattern. At such a time another arm 73 on shaft 12 contacts with one of the pins 74 on the end of the pattern drum 3 thereby causing the pattern drum to be moved to the next row of holes in the pattern. A suitable spring 75 contacting with one of the pins 74 insures that the drum 3 when moved by arm 73 will come to rest in such a position as to align the plungers 64 with the next row 50 of holes in the pattern. Whenever it is desired to lift the plungers 64 manually as when it is necessary to change the paper pattern for example, handle 76 may be moved in a counter-clockwise direction for this purpose. Pivotedly mounted on shaft 58 and 55 under the control of handle 76 are two mem-

bers 77 which support a metallic strip 78 running parallel to the drum underneath the plunger arms 59. The movement of handle 76 in a counter-clockwise direction causes the plunger arms 59 to be lifted to free the paper 70 pattern of all the plungers. Strip 78 has an upright projection 79 between each pair of the plunger arms 59 so as to serve as guides therefor. The pattern drum 3 and its associated cams and shafts may be located in a suitable housing 80 having a suitable cover 82. Housing 80 is suitably supported by a base 83 constituting a part of the supporting framework of the machine.

It will be understood, of course, that there are elements 40, 43, 53, 54, 55, 56, 62, 60, 59, 64 and 65 for each cylinder needle whereby each cylinder needle may be moved automatically in accordance with its associated pattern on the pattern drum. The drum 3 85 takes care of the needles in one quadrant, drum 4 in a second quadrant, drum 5 in a third quadrant and drum 6 in the remaining quadrant of the machine. If the plunger 64 in its downward movements finds no hole in the paper pattern the associated member 43 will be in such a position as to respond to the cylinder cam 49 and cause its needle to be raised to its maximum height whereby it enters into the knitting. If there is a small 90 hole in the paper so that only pin 65 enters, member 43 will be responsive to the cylinder cam 50 and the associated needle will be moved to an intermediate position. If there is a large hole in the paper pattern member 95 43 will not be responsive to either cam 49 or cam 50.

Fig. 3 is self-explanatory and shows how the cams 49 and 50 are attached to the cam cylinder 19.

Fig. 4 illustrates the mechanical construction of the two pattern drums 3 and 4. Drums 5 and 6 are, of course, similar. Drum 3 is shown with the paper pattern partly removed while drum 4 has a paper pattern 84 thereon. The shaft 85 for drum 3 is suitably pivoted at the points 86 and 87 to allow its free rotation when actuated by the bar 73. Member 86 has a suitable support 88 and member 87 has a support 89 through which it passes. Member 87 is held in place by a pivoted clamping arm 90 which is held against member 88 by a thumb screw 92. Clamping arm 90 being released allows member 87 to be pulled away 110 from drum 3 to allow the drum to be removed from the machine whenever it is desired. The paper pattern is held in position on the drum by pins 93 which project through correspondingly spaced holes near the edges of the pattern. Each pin 93 is adapted to be moved inwardly in its slot a sufficient distance so that the top of the pin is below the surface of the drum to facilitate 115 the removal of the paper pattern. This is 120 125 130

accomplished by having each pin 93 on one edge of the drum provided by a side pin 94 which works in an angular slot in a knurled ring 95. This is shown more in detail in Fig. 5 from which it will be apparent that when the pins 93 project above the surface of the drum the side pins are near the outer ends of the slots while the movement of ring 95 in a counterclockwise direction from the position shown in Fig. 5 will cause the side pins to move along towards the inner ends of the slots thereby retracting the pins 93. A similar knurled ring 95 is located at each end of the drums 3 to 6. The above description of drum 3 also applies equally well to the structure of the other three drums.

The machine of this invention is adapted to knit fabrics of widely different types since individual and automatic control is provided for each needle. While it is capable of knitting the ordinary Jersey cloth it is also particularly adapted to knit the type of multicolor fabric described and claimed in my U. S. Patent No. 1,426,576, of August 22, 1922. The fabric disclosed therein is of the multicolor type in which the loops in one section are of one color while the loops in an adjacent section are of a second color. The yarn which does not enter into the knitting in any particular section is carried behind the main loops, being interlocked with the loops in alternate wales to make a firm fabric without any dangling loops. Reference is made to the patent for a detailed description of this type of interlocked fabric.

The method of operation of the present machine will be better understood by reference to Fig. 6 which shows the operation schematically, the needles being placed in one plane for explanatory purposes. Cams 41, 46, 49, 50 and 96 are adapted to cause the operation of the needles for the passage of yarn carrier 1, while corresponding cams 91, 97, 98, 99 and 100 are adapted to cause the operation of the needles for the passage of yarn carrier 2. The cams and the yarn carriers are traveling of course from left to right.

For illustrative purposes the paper patterns on the drums 3 to 6 of Fig. 6 are designed to give in the front of the fabric loops of yarn 1 in one section controlled by drum 3 and loops of yarn 2 in another section of the cloth controlled by drums 4, 6 and 5 so as to give a striped effect. In that section containing loops of yarn 1, yarn 2 is interlocked in alternate wales in the rear of the fabric while in that section containing loops of yarn 2, yarn 1 is interlocked in alternate wales in the rear of the fabric as explained more in detail in my above mentioned patent. In Fig. 6 drums 3 and 6 have just been moved up one step since no cams are acting at this time on the needles controlled by drums 3 and 6. The mechanism de-

scribed in Fig. 2 has not yet caused the plungers to contact with the paper patterns of drums 3 and 6.

It furthermore will be assumed that in the showing of Fig. 6 the needles opposite drum 3 are holding loops of yarn 1; that the loops around the needles of drum 5 are of yarn 2; that the needles of drums 5 and 6 each have a loop of yarn 2; alternate needles also having caught yarn 1; and that the loops around the needles below the latches for drum 4 in position 104 are of yarn 2 with yarn 1 in a zigzag path in front of alternate needles and behind the remaining needles, while in position 105 the needles contain loops of yarn 2.

The plungers for drum 3 (only a few shown) will all find no holes in the paper pattern so that all of the needles controlled by drum 3 will be lifted to the full knitting position when cam 49 contacts with control members 43. This will cause the loops on the needles of drum 3 to fall below the open ends of the latches and the needles will then catch yarn 1, after which cam 46 will lower the needles of drum 3 causing them to cast their former loops and form new loops of yarn 1. Cam 96 will then raise the needles of drum 3 slightly as is customary to release the tension on the yarn somewhat. Before the cams 97 to 100 are ready to pass the control members 43 of drum 3, the drum 3 will have moved another step to present a different pattern which may, for example, be such that the yarn 2 will be interlocked in alternate wales of yarn 1 as will be described later.

With respect to drum 5 it is apparent that alternate holes in the pattern are large and the remainder are small so that alternate plungers go all the way in while the remainder go only half the way in. The needles associated with the plungers which go all the way in will not be raised due to either cam 49 or 50 due to the fact that their control members 43 are in such a position as not to be affected by cams 49 or 50. However, the control members 43 that are associated with the plungers which go only half way in will be lowered by cam 50. As shown in Fig. 6 alternate needles opposite drum 5 are raised thereby to such a position that their latches are opened but the old loops do not fall below the open ends of the latches. See, for example, the needle in position 102. The needles, however, are in such a position as to catch yarn 1, as shown in position 103. The alternate needles that catch yarn 1 are then lowered to substantially the level of the top of the needle cylinder by cam 41, the needles retaining both their old loops and the yarn 1. The needles which were not partially raised are then raised slightly by cam 96 as previously described. Those needles of drum 5 which

have caught yarn 1 also contain loops of yarn 2 previously formed, while the remaining needles contain only loops of yarn 2.

Attention is called to the fact that after 5 alternate needles have caught the yarn to be interlocked as in position 103, cam 41 or 91 brings the needles down only to approximately the top of the needle cylinder as in position 101, while when ordinary loops are 10 being formed cam 46 or 99 brings the needles appreciably lower (see position 111) after which they are subsequently raised slightly by cam 96 to a position, the equivalent of position to which the needles are lowered by 15 cam 41 or 91. The feature of having the alternate needles for interlocking purposes lowered to a lesser degree than for ordinary knitting is of considerable advantage when it is desired to have the interlocked 20 yarn drawn fairly tight.

Only a few needles for drum 6 are shown. The plungers are raised from the paper pattern as the drum has just been moved to present a fresh portion of the pattern and 25 the previous row of perforations had been such as shown for drum 5, namely, one causing the interlocking of yarn 1 in alternate wales of the fabric formed by the needles of drum 6. That is, alternate needles of 30 drum 6 contain yarn 1 as well as loops of yarn 2 while the remaining needles contain only loops of yarn 2. The new portion of the pattern for drum 6 has no holes in it so that all the needles of drum 6 will knit loops 35 of yarn 2 when it passes due to the action of cams 98, 99 and 100.

The paper pattern for drum 4 shows no holes for the plungers so that due to action 40 of cams 98, 99 and 100 they are knitting loops of yarn 2. A detail of the interlocking feature is shown, for example, in position 45 104 and adjacent thereto. The needles have been fully raised due to cam 98 so that the old loops of yarn 2 have fallen below the open latches. Yarn 1 is also below the open 50 latches being in front of alternate needles and behind the remaining needles. It is with shown adjacent position 105. After the new 55 loops have been formed cam 100 raises the needles slightly as previously described.

It has thus been shown how the needles 60 of drums 5, 6, and 4 knit loops of yarn 2, the needles of drum 3 knit loops of yarn 1, while each yarn is interlocked in alternate wales of the loops of the other yarn. It is 65 of course understood that the character of the fabric may be varied from time to time by variations in the nature of the pattern paper. The same general operation may also be applied to any desired number of yarns, two yarns being merely representative.

The general aspect of the machine of this 65 invention will be better understood by the

plan view of Fig. 7 where a horizontal section has been made in several planes. Yarn carrier 1 is shown attached to rotating ring 20. The dotted lines on ring 29 indicate the cam head which causes the movement of the 70 sinkers 28. The needle cylinder 24 is shown on the extreme left with the needle slots. At the point 106 the ring 20 is broken away showing the grooves in the sinkers and between the sinkers the supporting plate 107 is 75 visible. This plate 107 rests on a ledge 108 on the outside of the needle cylinder 24 as shown in Fig. 2 which accounts for projections from the needle cylinder just below where plate 107 is broken off. Immediately 80 below the section showing ledges 108 another section is taken showing the normal needle grooves. At the right is shown member 36 with its radial grooves 37 and its circumferential groove with wire 39 there- 85 in. On top of wire 39 rests the control arms 40. Near the center of the figure are shown the slots 44 provided for the upper ends of control members 43. Immediately below at the position 109 the slots are longer being at 90 a cross section in the region opposite the top of member 36. Position 110 shows the slots in the upper part of plate 33, while at the point 112 the slots for the lower portion of plate 33 are shown wherein work the special 95 members 52. It is believed that the other parts of Fig. 7 will be easily understood by reference to Fig. 2.

Fig. 8 shows the position control member 43 takes when the plunger associated therewith passes all the way in the pattern paper. Under the action of the spring 54, as shown in Fig. 2, the member 52 is pulled to the left thereby moving the lower part of member 43 to the left so that the cams 49 or 50 will 105 not contact with the projection 48.

Fig. 9 shows the position of the various control members after cam 49 of Fig. 2 has passed and caused control member 43 to assume its lowermost position. The lower 110 end of member 43 is near the bottom of the U-shaped part of member 52 and member 52 is in its extreme right position. The upper end of member 43 is still inside slot 44 although in its lower part. The lowering of 115 member 43 has, of course, raised the associated needle to its full knitting position.

The character of the interlocked fabric prepared by the machine of this invention 120 may be better understood by referring to my prior Patent No. 1,541,230, of June 9, 1925.

The machine of this invention is not limited to the knitting of an interlocked fabric since it is of general application being capable of ordinary knitting, such as Jersey 125 cloth. It is evident that this invention provides for the individual control of all the cylinder needles so that a complicated design may be formed in the knitted fabric. This is accomplished even with interlocked cloth 130

with only one type of needle. That is all the cylinder needles may and should be exactly alike, thereby rendering unnecessary the use of needles of several types as heretofore have been used. The needles are shown to be of the latched type although this invention may be used with other types of needles such as spring needles.

As shown in Fig. 6 it is desirable to have 10 the pattern drums stepped around to a new position at the time when their needles are not occupied in the knitting. Thus, as shown in Fig. 6, as drums 4 and 5 are knitting, drums 3 and 6 should be stepped 15 around; and similarly while drums 3 and 6 are knitting drums 4 and 5 should be stepped around to a new portion of the fabric. As shown in Fig. 1, this means that alternate 20 drums will be moved while the other two 25 are knitting. The time for the stepping around of one of the drums is controlled as shown in Fig. 2 by the relative position of cam 73 on shaft 12. This cam 73 can be so positioned as to cause the associated drum 30 to step around at the time the needles associated with the drum are not engaged in the actual knitting. The same general procedure may also be followed with a greater number of drums or a greater number of 35 yarns or both.

It is to be understood that the following claims are intended to cover all of the generic and specific features of the invention herein described, and all statements of the scope of the invention, which as a matter of language might be said to fall therebetween.

The invention claimed is:

1. A knitting machine comprising a circular row of needles, a projection on the shank 40 of each needle, a pivoted arm individual to each needle, one end of said arm being coupled to said projection, whereby the movement of said arm causes the upward and downward movement of its associated needle, a plurality of yarn carriers, rotating cam means for causing the other end of said arm to be given a partial downward movement, a second rotating cam means for causing said other end to be given a full 45 downward movement, a third rotating cam means for producing an upward movement of said other end, and pattern mechanism for causing when one yarn carrier is passing said first cam means to be effective on alternate arms of a given group while the remaining arms of said group are unaffected by either of said first two cam means, and for causing, when a second yarn carrier is passing, said second cam means to be effective 50 on all arms of said group.

2. A knitting machine comprising a circular row of needles for combining a plurality of independent yarns into a fabric, and cam means to advance and retract the 55 needles of a group to receive one of said

yarns and to knit loops thereof, and additional cam means to advance certain of the needles of said group a distance sufficient to receive a second of said yarns but insufficient to allow the yarn previously looped 70 to escape therefrom and to subsequently retract said certain needles to a position relatively closer to the yarn receiving position than when said certain needles are retracted for regular loop knitting as produced by 75 said first cam means.

3. A knitting machine comprising a circular row of needles, a grooved stationary element carrying said needles, all of said needles being of similar shape and size, a 80 control member individual to each needle for causing the upward and downward movement of its associated needle, a plurality of yarn carriers, rotating cam means for causing said members to produce a partial upward movement of the associated needles, a third rotating cam means for producing a full downward movement of said needles, and pattern 85 mechanism simultaneously selecting a group of said members for causing when one yarn carrier is passing said first cam means to be effective on alternate members of a given 90 group of needles while the remaining members of said group are unaffected by either of said first two cam means, and for causing when a second yarn carrier is passing said second cam means to be effective on all 95 members of said group.

4. A knitting machine comprising a circular row of needles, a control member individual to each needle for causing the upward and downward movement of its associated needle, a plurality of yarn carriers, rotating cam means for causing said members to produce a partial upward movement of the associated needles, a second rotating cam means for causing said members to produce a full upward movement of the associated needles, a third rotating cam means for producing a full downward movement of said needles, a fourth rotating cam means for producing a partial downward movement of said needles, and pattern mechanism for causing, when one yarn carrier is passing, said second cam means to be effective on all members of a group after which said third cam means is effective to lower said 105 needles, said pattern mechanism also causing, when a second yarn carrier is passing, said first cam means to be effective on alternate members of said group and later causing said fourth cam means to lower said 110 alternate needles.

5. A knitting machine of the circular type comprising a circular row of needles, a projection on the shank of each needle, a pivot- 120 ed arm individual to each needle and having 125

one end embracing said projection whereby the movement of said arm causes the advance and retraction of its associated needle, a control member for each of said arms, said

5 members being capable of movement in both a horizontal and a vertical plane, pattern mechanism for controlling individually the positions of said members in a horizontal plane, and rotating cam means for causing a 10 movement of said members in a vertical plane.

15 6. A knitting machine of the circular type comprising a circular row of needles, a pivoted arm individual to each needle for causing the advance and retraction of the associated needle, a control member for each of said arms, slotted means for receiving said members to permit one end thereof to be moved in a vertical plane with negligible motion in a horizontal plane while permitting the opposite ends of said members to be moved in a horizontal plane, pattern mechanism for controlling individually the positions of the lower ends of said members in a horizontal plane, and rotating cam means for causing a movement of said members in a vertical plane.

20 25

7. A knitting machine comprising a circular row of needles, a grooved stationary element carrying said needles, a control member for each needle for advancing or retracting its associated needle, a plurality of yarn carriers, rotating cam means for causing said members to produce a partial advancement of the associated needles, a second rotating cam means for causing said members to produce a full advancement of the associated needles, a third rotating cam means for producing a retraction of said needles, and pattern mechanism for simultaneously selecting a group of said members and for causing when one yarn carrier is passing said first cam means to be effective on alternate members of said group while the remaining members of said group are unaffected by either of said first two cam means, and for causing when a second yarn carrier is passing said second cam means to be effective on all members of said group, said pattern mechanism also causing the number of members in said group to vary from time to time in a predetermined manner.

8. A knitting machine comprising a circular row of needles, a grooved stationary element carrying said needles, a control member individual to each needle for causing at times the advancement of its associated needle, a plurality of yarn carriers, rotating cam means for causing said members to produce a full advancement of the associated needles, a second rotating cam means for producing a partial advancement of said needles, means for retracting said needles and automatic pattern mechanism for simul-

taneously selecting a group of said needles and responsive to the passage of one yarn carrier to cause said first cam means to be effective on all of said group of needles and responsive to the passage of a second yarn carrier to cause said second cam means to be effective to partially advance only a fractional portion of the needles of said group, the remainder of the needles of said group being unaffected by said first and said second cam means, said pattern mechanism when moved to a different position by the operation of the machine being responsive to the passage of said first yarn carrier to cause said second cam means to be effective to advance only a fractional portion of the needles of said group, the remainder of the group being unaffected by said first and said second cams and being responsive to the passage of said second yarn carrier to cause said first cam means to be effective to advance all the needles of said group, said pattern mechanism also causing the number of needles in said group to vary from time to time in a predetermined manner.

9. A knitting machine comprising a circular row of needles, a grooved stationary element carrying said needles, a control member individual to each needle for causing at times the advancement of its associated needles, a plurality of yarn carriers, rotating cam means for causing said members to produce a full advancement of the associated needles, a second rotating cam means for producing a partial advancement of said needles, means for retracting said needles, and automatic pattern mechanism for simultaneously selecting a group of said needles and responsive to the passage of one yarn carrier to cause said first cam means to be effective on all of a group of said needles and responsive to the passage of a second yarn carrier to cause said second cam means to be effective to advance only a fractional portion of the needles of said group, the remainder of the needles of said group being unaffected by said first and said second cam means, said pattern mechanism when moved to a different position by the operation of the machine, being responsive to the passage of said first yarn carrier to cause said second cam means to be effective to advance only said remaining needles of the group while said fractional portion of said group remain unaffected by said first and said second cam means and being responsive to the passage of said second yarn carrier to cause said first cam means to be effective to advance all the needles of said group, said pattern mechanism also causing the number of needles in said group to vary from time to time in a predetermined manner. 120 125

10. A knitting machine comprising a cir-

10. A knitting machine comprising a circular row of needles, a grooved stationary element carrying said needles, a plurality of 139

yarn carriers, a control element individual to each needle for causing at times the advancement of each needle, a projection on each of said control elements, rotating cam 5 means for contacting with said projections for fully advancing said needles, a second rotating cam means contacting with said projections for partially advancing the said needles, a third rotating cam means for re- 10 tracting said needles, and pattern mechanism for simultaneously causing, when one yarn carrier is passing, all of a group of said elements to be moved to place their projections in the path of said first cam means and for 15 causing, when a second yarn carrier is passing, a fractional portion of said group of control elements to be moved to place their projections under the control of said second cam means while the remainder of the con- 20 trol elements of said group are unaffected by said first and said second cam means, said pattern mechanism also causing the number of control elements in said group to vary 25 from time to time in a predetermined manner.

11. A knitting machine comprising a circular row of needles, a grooved stationary element carrying said needles, a plurality of yarn carriers, a rotating cam adapted to 30 produce a partial advancement of every needle in said row, a second rotating cam adapted to produce the full advancement of every needle in said row, means for retracting said needles and pattern mechanism for 35 selecting a group of said needles and for simultaneously causing, when one yarn carrier is passing, said second cam to produce the full advancement of all needles of said group, for subsequently selecting a limited 40 number of said group and for causing, when said second yarn carrier is passing said first cam, to produce the partial advancement of said limited number of needles, while the remainder of the needles of said group are 45 unaffected by said first and said second cams, said pattern mechanism also causing the number of members in said group to

vary from time to time in a predetermined manner.

12. A knitting machine comprising a row 50 of needles, a grooved stationary element carrying said needles, a control member individual to each needle, a yarn carrier, a rotating cam for causing said members to partially advance said needles, a second rotating 55 cam for causing said members to fully advance said needles, means for retracting said needles, and pattern mechanism for simultaneously selectively operating a group of said control members to cause one of said selected 60 members to be actuated by said first cam, when said yarn carrier is passing, to subsequently cause said selected member to be actuated by said second cam in a second 65 passage of said yarn carrier, and subsequently to cause said selected member to be free of actuation from both said first and said second cams during another passage of said yarn carrier.

13. A knitting machine comprising a circular row of needles for combining a plurality of individual yarns into a fabric, cam means to advance alternate needles of a group to a position sufficient to receive a 70 yarn but insufficient to allow a yarn previously looped to escape therefrom and to subsequently retract said alternate needles to a normal retracted position, a second cam 75 means to advance and retract all the needles of said group to receive a second of said 80 yarns and to knit loops thereof, said second cam retracting said needles to a position relatively farther away from the yarn receiving 85 position than the normal position occupied by said alternate needles after retraction by said first cam means, and additional cam means operative after said second cam means for bringing all of the needles of said group to the said normal retracted position.

In witness whereof, I hereunto subscribe 90 my name this 11th day of September A. D., 1925.

VINCENT LOMBARDI.
